UNITED STATES PATENT OFFICE.

JOHN LINDALL, OF BOSTON, MASSACHUSETTS.

RAILWAY-CAR.

1,110,394.

Specification of Letters Patent. Patented Sept. 15, 1914.

Application filed April 19, 1912. Serial No. 691,369.

To all whom it may concern:

Be it known that I, JOHN LINDALL, a citizen of the United States, residing in Boston, county of Suffolk, and State of Massachusetts, have invented an Improvement in Railway-Cars, of which the following description, in connection with the accompanying drawings, is a specification, like letters on the drawings representing like parts.

This invention relates to a railway car especially designed and adapted for use on electric railway systems, and more particularly on surface railway systems which are provided with tracks having curves of short radii.

The present invention has for its object to provide a multiple unit car which is capable of being run on tracks having curves of short radii without an abnormal or objectionable overhang of the car, and which is of a carrying capacity largely in excess of a single or unit car of a length which has the same overhang.

The invention further has for its object to provide such a multiple unit car, which is capable of being operated by a single conductor and motorman.

The invention also has for its object to provide such a multiple unit car, in which the passageway from one unit to another is maintained of substantially the same width, when the car is rounding a short curve, as when on a straight track.

To this end, the multiple unit car is provided with a plurality of main car body sections or units, and with an intermediate car body section or unit, which may and preferably will be shorter in length than said main units, and is pivotally connected thereto near their adjacent ends to be supported thereby. The main units are mounted upon one or more trucks, each capable of being run on street tracks having curves of short radii, and each of said main units is made of such length as will give a maximum carrying capacity and yet avoid an abnormal overhang of the end of the car body as it is rounding a curve of short radius. Provision is made for utilizing the intermediate car body section or unit, as the entrance into and exit from the main car body sections or units, as will be described. The main units may be pro-

vided with the usual trolley poles and 55 wheels which engage the overhead trolley wire, and provision is made, whereby the trolley poles and wheels on both main units may be controlled by the conductor from within the intermediate unit. Provision is 60 also made for closing the sides of the passageways from the intermediate unit to the main units, and further for pivotally supporting the intermediate unit in a superior manner as will be described. These and 65 other features of this invention will be pointed out in the claims at the end of this specification.

Figure 1 is a side elevation with parts broken away of a multiple unit electric railway car embodying this invention. Fig. 2, a plan of the car shown in Fig. 1. Fig. 3, a detail in plan to be referred to. Fig. 4, an underside view on an enlarged scale to show the framework of the adjacent ends of a 70 main car body section and the intermediate section. Fig. 5, a cross section on the line 5—5, Fig. 4 looking in the direction of the arrow. Fig. 6, a detail in side elevation on an enlarged scale with parts broken away, 75 of the adjacent ends of the intermediate and a main car body section, Fig. 6^a a detail of the guide for the trolley rope to be referred to. Fig. 7, a horizontal section of the intermediate car body section taken below 80 the roof thereof to show the manner of controlling the various operating parts of the car and also the entrance and exit of the passengers. Fig. 8, a detail to be referred to. Fig. 9, a detail in elevation of two 85 co-operating doors and their operating mechanism. Fig. 10, a detail of a portion of the door operating mechanism. Fig. 11, a horizontal section on the line 11—11. Fig. 12, a detail of a step and its operating 90 mechanism, and Fig. 13, a detail of the railing within the intermediate car body section. 95

Referring to the drawings, *a* and *b* represent the main car body sections or units, 100 *c* the intermediate car body section or unit of a multiple unit electric railway car embodying this invention.

The main units *a*, *b*, are mounted upon trucks *7*, *i.e.*, of any suitable construction capable of traveling on curves of substantially short radii in street railway trucks, such as now exists in cities and especially cities hav-

ing narrow streets. In the present instance the main units *a*, *b*, are two ordinary street railway cars, each of a length which enables them to be used on tracks having curves of short radii without an objectionable overhang, and each having one end modified to enable it to be utilized in forming a main car body section or unit of the improved car. To this end, each of the car bodies or units *a*, *b*, is cut off at one end substantially flush with the usual doorway leading into the car body at said end, that is to say, the usual platform and bonnet are removed, and the end construction of the car body is reinforced to enable it to be utilized to form part of the multiple unit car. Inasmuch as the reinforcement for both car bodies or units *a*, *b*, is the same, a detailed description of one will suffice, to wit, that of the car body *a*. In the present instance, the reinforcement is effected by means of a metal cross bolster 10, see Figs. 1, 4 and 5, which is approximately an inverted arch in shape and is secured at its ends by bolts or otherwise, to the end sill 12 of the car body *a*. The cross bolster 10 has riveted or otherwise secured to one side at or near its center, braces 13, 14, which diverge and are extended back under the car body *a* and secured thereto at their ends in any suitable manner. The cross bolster 10 is preferably made of channel iron and is provided with a substantially flat central portion 15, to which is secured the lower plate or member 16 of a center bearing, with which coöperates the upper plate or member 17, which is secured to the intermediate car body section or unit *c* as will be described.

The cross bolster 10 may and preferably will be secured to the end sill 12 between its ends by vertical tie bars or braces 18. The end sill 12 may and preferably will have secured to it side bearings, preferably rollers 19 mounted on shafts or pins 20 supported by hangers 21 secured to the end sill 12.

The intermediate unit or car body section, *c*, is made to correspond in general appearance externally to that of the main car body sections *a*, *b*, so as to harmonize therewith, and said intermediate unit is composed of a floor frame, which is substantially rectangular in shape and composed of metal side bars or sills 22, 23, end cross bars or sills, 24, only one, 24, of which is shown in Fig. 4, longitudinally extended center beams or bars 25 and suitable braces intermediate the end sills. The center beams or bars 25 are extended beyond each end sill, 24, and are connected on their under side at or near their outer ends by a cross bar 26, to which is secured the upper plate or member 17 of the center bearing, which is provided on its under side with a cup or socket 28, see Fig. 6, for the reception of the projection 29 on the lower

bearing plate 16. The center bearing is provided with a king bolt 30 extended down through the end sill 12 and through the bearing plates 17, 16 to the underside of the cross bolster 10, where it may be provided with a key 32, see Fig. 5. If desired the upper bearing member 17 and the cross bar 26 may be made in one piece. The center bars or beams 25 beyond the end sill 24 are tied together by cross braces 33, and are also secured to the end sill 24 by inclined braces 34. The center beams or bars 25 may and preferably will have secured to them one end of curved bars 36, which extend between the cross bolster 10 and the end sill 12 of the car body section *a* and are provided with return bends 37, which are fastened to a cross bar 38 secured to the center bars or beams 25. The curved side bars 36 constitute the lower side bearing plates with which the rollers 19 are designed to engage when the car body section *a* is tilted slightly. The lower bearing plates or bars 36 are supported below the rollers 19 by inclined bars or arms 39 extended in opposite directions from the center bars or beams 25, see Fig. 5.

The floor frame of the intermediate section has secured to it the flooring, 40, which may be of wood or other suitable material, and said flooring may be provided with inclined side ends 41, which extend inwardly from the side sills 22, 23 of the floor frame toward the projecting portions of the center bars or beams 25, so as to leave a space 42 between the end of the main unit and the side sills of the intermediate unit, to allow for substantial, lateral or side movement of one unit with relation to the other when traveling around a curve of substantially short radius, as for instance, when the car is turning around a corner of a substantially narrow street. The floor supporting frame of the intermediate unit also has erected upon it the side walls 43, 44, end walls 45, 46, and the roof 47 of the intermediate unit, and the roof 47 may and preferably will be made to correspond in general form and structure to the roofs of the main units *a*, *b*.

The intermediate unit *c* is provided at its ends with openings or ways 48, see Fig. 7, from which extend the portions 49 of the flooring covering the projecting ends of the center beams or bars 25, which extend under the end sills 12 of the main units *a*, *b*, see Fig. 6, and form platforms from the intermediate unit to the main units. The intermediate unit *c* is preferably provided at each end with a bonnet 50, suitably shaped to form a gutter 51, see Fig. 6, for shedding the water.

The platforms 49 on the intermediate unit *c* may be closed at their sides and top, which may be accomplished as herein shown by providing the end walls of the intermediate

unit with projecting arch shaped frames 52, and providing the end walls of the main units *a*, *b* with similar arch shaped frames 53, which are smaller than the frames 52 and are separated therefrom by sufficient space to permit of lateral movement of one frame with relation to the other in rounding a curve of short radius. The space between the projecting frames 52, 53 may be closed by a flexible member 54 of canvas or other suitable material which is secured to said frames.

The intermediate unit *c* may be used as the means for entrance into and exit from the main units *a*, *b*, whereby a single operator can collect the fares, attend to the opening and closing of the doors, and further can attend to the trolley poles when the trolley wheels leave the trolley wire, all from within the intermediate unit. To this end the side walls 43, 44 of the intermediate unit *c* are provided with suitable doors and with steps leading to the doorways and capable of being raised and lowered simultaneously with the closing and opening of the doors. Inasmuch as the doors and steps on both sides of the car body unit *c* are of like construction and their operating mechanisms are also of like construction, a detailed description of these parts on one side of the said intermediate unit will suffice. In the present instance, the unit *c* is provided on each side with end corner posts or uprights 55, 56, and three intermediate uprights 57, 58, 59, see Fig. 7, which are separated to form four doorways 60, 61, 62, 63, with each of which coöperates a pair of doors 64, 65, and a step 66. The doors 64, 65 of each pair are secured to vertically arranged pivot rods or shafts 67, 68, see Figs. 7 and 9, suitably journaled or supported by the framework of the intermediate unit *c* to turn through an arc of substantially 90°, so as to swing the said doors from their closed position outwardly into a position substantially at right angles thereto and vice versa. This movement of the doors 64, 65 may be effected by suitable mechanism under control of the conductor within the unit *c*, and in the present instance, I have shown one construction of mechanism for accomplishing this result. To this end, the pivot 68 for the door 65 is provided at its upper end with a crank 70, see Fig. 9, which is connected by a link 71 with a crank 72 on the pivot 67 for the door 64, said cranks being extended in substantially opposite directions. The pivot 67 for the door 64 is provided with a second crank 73, which is located below the floor supporting frame of the unit *c* and is connected by a link 74 to an elbow lever 75, see Fig. 10, pivoted to a hanger 76 depending from a suitable support 77, which may be secured to or form part of the support-

ing frame of the intermediate unit *c*. The elbow lever 75 has connected to it a vertical bar or rod 78, which extends up through a suitable hole 79 in a plate 80, set in the floor 40 of the unit *c*, where it is accessible to the foot of the conductor. The rod or bar 78 constitutes one form of foot pedal and is provided with notches 81, 82 for engagement with a wall of the hole 79 to lock the doors in their opened and closed positions, until released by the operator. When the foot pedal 78 is in the position shown in Fig. 10, the doors controlled thereby are closed, and to open the doors the operator moves the pedal in the direction of the arrow 83, which releases the pedal and permits a spring 84, see Fig. 7, to contract and move the link 74 so as to swing the doors open. When the doors are closed the spring 84 is expanded or placed under tension. Each doorway in the present instance has cooperating with it a step 66, which is pivoted at 85 to a hanger 86, depending from the car body unit *c*, see Fig. 12, and said step is connected to the link 74, so as to be operated thereby and folded up when the doors are closed, and lowered when the doors are opened. In the present instance, the link 74 has pivoted to it one end of a rod or link 87, having at its other end a head 88, having a socket within it for the reception of a ball or knob 89 on the end of an arm 90, secured to the step 66 and extended through a slot 91 in said head, see Fig. 12. By reference to Fig. 7, it will be seen that when the link 74 is moved in one direction to close the doors 64, 65, the link 87 is also moved so as to fold the step 66 into its vertical position, and when the link 74 is moved in the opposite direction, the link 87 is moved in the direction of the arrow 93 in Fig. 12 to lower the step. The spring 84 is represented in Fig. 7 as having one end connected with a pin 94 on the link 74 and its other end connected with a stationary part 95 of the unit *c*.

Provision is made for separating the interior of the car section or unit *c*, so that the doorways 61, 62 form the entrances, and the doorways 60, 63 the exits into and from said unit, and for this purpose, the unit *c* is provided with two sets of vertical uprights or posts located between the center of the car section *c* and the end doorways 48. In the present instance each set is shown as composed of three posts or uprights 96, 97, 98, arranged transversely of the unit *c* with the posts 96, 97 located toward the center of the unit. The posts 96, 97 are stationary and are connected by cross bars 99, which prevent passage between said posts, and either of the passages between the stationary posts and the sides of the unit *c*, may be closed by a horizontal rod or bar 100, which is attached at one end to the vertical post 98, 125

which is adapted to have its lower end stepped in a suitable socket in the floor of the unit *c*, and to be retained in its vertical position by a lug 101, see Fig. 13, on the post 5 engaging a slotted lug or ear 102 attached to the side frame of the unit *c*. The horizontal bar 100 may be detachably secured to either of the stationary posts 96, 97, by a bolt 104 actuated by a spring 105. The post 98 is 10 capable of being vertically moved to disengage its lug 101 from the lug or ear 102, when the bolt 104 is withdrawn, so as to permit the cross bar 100 and post 98 to be used in connection with the stationary post 96 15 and close the passageway 205 between the post 96 and the side of the unit *c*, and to open the passageway 106 between the post 97 and the other side of the unit *c*.

As represented in Fig. 7, the unit *c* is 20 provided with two sets of operating pedals 78 for the doors and steps, and between the same is a space 108, designed to be occupied by a fare box or other receptacle for fares. The conductor can stand on either side of 25 the space 108 according to which set of pedals he is to operate. Provision is made for enabling the conductor to replace the trolley wheel from within the unit *c*, and to this end the roof of the car section *c* is 30 provided with suitable openings in its opposite ends, through which are passed the trolley ropes 110, 112 attached to the trolley poles 113, 114 on the main units *a*, *b*. These trolley ropes may be connected with trolley 35 tenders 115, 116 of ordinary construction such as are now commonly used on electric street railway cars, and may be detachably secured to cross bars 117 connecting the stationary posts 96, 97 of each set of posts. 40 The openings in the roof through which the trolley ropes are passed, may be closed by windows, only one, 120, of which is shown, which is supported by a lever 121 located within the unit, and capable of being turned 45 by the conductor, when it becomes necessary to manipulate the trolley rope in order to replace the trolley wheel on the trolley wire. The window 120 and its casing are constructed in a manner well understood, so as 50 to make a practically water tight joint when the window is closed. The lower portion of the window casing is provided with a slot, groove or opening on its inner surface in which is located a bushing or guide 125, see 55 Fig. 6^a, provided with a longitudinal opening 126, of sufficient width to allow the trolley cord or rope to be passed into and removed from the bushing, so that when the window is closed, the trolley rope is free 60 to run through the bushing, as the said rope is taken up and paid out by the tender, when the trolley wheel is on the wire and the car is in motion, and so that when the window is opened, the trolley rope can be 65 slipped out of the bushing by the conductor,

and moved sideways in the window opening for the full width of the same, to manipulate the trolley pole and replace the trolley wheel on the wire when the necessity for so doing arises.

By reference to Fig. 7, it will be seen that the passengers can enter through the center doorways 61, 62, pass by the conductor and into either of the main car sections or units *a*, *b*, as indicated by the arrows 130, and when leaving the said main units, they pass into the intermediate unit *c* and out through the separate doorways 60, 63, whose doors are at such time opened, the course taken by the passengers when leaving the car being indicated by the arrows 131. Provision is also made for closing the space between the intermediate unit *c* and the main units *a*, *b*, so as to prevent persons riding on the outside of the car between the units, and also to safeguard against possible accidents, and to this end cross rods or bars 132 are pivotally secured at their lower ends to the intermediate and main units *c*, *a*, *b*, and have their other or upper ends in sliding engagement with guide rods or bars 133 attached to said units.

In the present instance I have described the invention as embodied in a railway car in which are utilized as the main units, two old style cars having comparative short bodies and of limited carrying capacity, and such as are now used somewhat and formerly were largely used in cities having tracks provided with curves of relatively short radii, and a new car body section or unit interposed between the same and pivoted to the main units, but it is not desired to limit the invention in this respect as the multiple unit car may be of entirely new construction.

By pivoting the intermediate unit to the main units at or near the ends of the main units, the said units are permitted to have a substantial, lateral movement, one with relation to the other, in rounding a curve of short radius, without contracting or narrowing up, to any material extent on the passageways from one unit to the other, and said passageways may be provided with movable side walls in the form of curtains 140, see Fig. 7, which serve to provide substantially straight side walls, both when the units are in alinement on a straight track and when out of alinement when one is on a curve.

From the above description, it will be seen that the main units of the multiple unit car are of maximum unit length with a maximum overhang, that is, with an overhang which does not project beyond the outer rail of the curve of short radius to such extent as would be dangerous to persons standing on cross walks, or to vehicles using the streets and especially narrow streets,

consequently a railway car is obtained which is of increased carrying capacity and is capable of being operated on tracks having curves of short radii, such as now exists in tracks laid in narrow streets, without danger to the users of the streets and further without danger to the cars on tracks on intersecting streets, and which is also capable of being operated by a conductor and motorman at a minimum expense. As a result street railway systems are able to furnish better accommodations to the public; increase their earning capacity by their ability to run long cars on their tracks having short curves without changing the tracks, which in some streets it would be well nigh impossible to do and leave sufficient room for the use of the street by others; and without increasing the number of operators on the car. Furthermore, the present invention enables street railway systems now operating, to effect a very great saving, in that they can utilize the short cars now rapidly growing obsolete, and convert them into main units of the multiple unit car, thereby effecting a very considerable saving in this respect. I have herein shown one construction of multiple unit car embodying this invention, but it is not desired to limit the invention in this respect. Furthermore it is not desired to limit that feature of the present invention which provides for the trolley pole located outside of the car to be manipulated by the conductor from within the car, so that the trolley rope may run in and out of the car under normal conditions of use, and so that it may be moved laterally of the car from within the same by the conductor, when it becomes necessary to replace the trolley wheel on the trolley wire, as this feature can be used to advantage with other forms of cars than the multiple unit herein shown.

Claims:

1. In a railway car, in combination, a plurality of main car body units mounted on trucks capable of being run on tracks having curves of substantially short radii without an abnormal overhang, and an intermediate car body unit pivoted to the adjacent ends of said main car body units to be supported thereby and to move laterally with relation thereto, said intermediate unit being provided with movable doors in its side and with means within it for forming passages leading to and from the main units.

2. In a railway car, in combination, a plurality of main car body units mounted on trucks capable of being run on tracks having curves of substantially short radii without an abnormal overhang, and an intermediate car body unit provided with a floor supporting frame and with side and end walls and a roof erected upon said frame, said end walls having openings leading to

openings in the ends of the main units, and said floor supporting frame having substantially central projecting end portions extended under the ends of the main units and pivoted thereto.

70

3. In a railway car, in combination, a plurality of main car body units, each of maximum unit length and capable of traveling on a track having a curve of short radius without an abnormal overhang, trucks to support said main units, and an intermediate car body unit interposed between said main units and pivotally secured thereto to be supported thereby and to move laterally with relation thereto.

80

4. In a railway car, in combination, a plurality of main car body units provided with openings in their adjacent ends, and an intermediate car body unit having a floor supporting frame and a roof erected upon the same, means for pivoting said frame to said main units to permit of lateral movement of one with relation to the other, and to support said intermediate car body unit by said main units, and trucks capable of being run on tracks having curves of short radii and upon which said main units are mounted.

85

5. In a railway car, in combination, a plurality of main car body units, each of maximum unit length and capable of traveling on a track having a curve of short radius without an abnormal overhang, trucks to support said main units, and an intermediate car body unit interposed between said main units and provided in its side with a common entrance leading to the main units and with separate exits from said main units, and means to close said entrance and exits.

95

6. In a railway car, in combination, a plurality of main car body units, each of a maximum unit length capable of traveling on a track having a curve of substantially short radius with a minimum overhang, trucks to support said main units, and an intermediate unit pivoted to the main units near the ends thereof to be supported thereby and to permit lateral movement of one unit with relation to the other on a substantially short curve of the track without substantially narrowing the passageways leading from the intermediate unit to the main units.

105

7. In a railway car, in combination, a plurality of main car body units, each of maximum unit length and capable of traveling on a track having a curve of short radius without an abnormal overhang, trucks to support said main units, and an intermediate car body unit provided with a door in its side and interposed between said main units and pivotally secured thereto and supported thereby.

115

8. In a railway car, in combination, an intermediate unit provided with a floor supporting frame, side and end walls and a roof

120

125

130

erected upon said frame, one of said side walls having a doorway, and main car body units located at opposite ends of said intermediate unit and pivotally connected therewith to support the same and permit lateral movement thereof.

9. In a railway car, in combination, an intermediate unit provided with a floor supporting frame having substantially central projecting end portions, a floor laid upon the said frame and said projecting end portions, side and end walls and a roof erected upon said frame to form a car body section having platforms projecting therefrom, a door in one of said side walls, and main units provided with cross bolsters, center lower bearing plates secured to said cross bolsters, center upper bearing plates secured to the under side of the projecting end portions of the frame of the intermediate unit and coöperating with said lower bearing plates, and means for pivotally connecting said bearing plates, substantially as described.

25 10. In a railway car, in combination, a plurality of main car body units, provided with openings in their adjacent ends and having cross bolsters secured to their under sides near the adjacent ends thereof, center bearing members supported by said bolsters, an intermediate car body unit having a floor supporting frame provided with substantial central projecting end portions, side and end walls and a roof erected upon said frame, 35 center bearing members secured to said projecting portions and coöperating with the bearing members on said cross bolsters, and trucks capable of being run on tracks having curves of short radii and upon which 40 said main units are mounted.

11. In a railway car, in combination, a plurality of main car body units provided with openings in their adjacent ends, trucks capable of running on tracks having curves 45 of substantially short radii, and an intermediate car body unit having a floor supporting frame pivoted to the main units to be supported thereby, and having side and end walls and a roof erected upon said frame, 50 a door in one of said side walls, and mechanism operable from within said intermediate unit to operate said door.

12. In a railway car, in combination, a plurality of main car body units capable of 55 traveling on a track having a curve of substantially short radius without an abnormal overhang, trucks to support said units, and an intermediate car body unit interposed between said main units and pivotally secured thereto to be supported thereby and to move laterally with relation thereto.

13. In a railway car, in combination, a plurality of passenger carrying sections, and an intermediate loading and unloading section having a floor supporting frame ex-

tended under the passenger carrying sections and pivoted thereto, substantially as described.

14. In a railway car, in combination, a plurality of passenger carrying sections and an intermediate loading and unloading section interposed between said passenger carrying sections and pivotally secured thereto to be supported thereby and to move laterally with relation thereto.

15. A car including a body part having end portions and an intermediate portion, said intermediate portion having a lower floor level than the end portions, and hinge connections intermediate the intermediate and end portions.

16. A car having end portions and an independent intermediate portion swivelly connected to the end portions, the flooring of the end portions being at a higher elevation than the flooring of the intermediate portion and a doorway in the side of the intermediate portion.

17. A car having end portions including supporting trucks and an intermediate portion pivotally connected to the end portions, the flooring of the intermediate portion being at a lower level than the flooring of the end portions, side doorways for the intermediate portion, doors therefor, and means arranged inside the intermediate portion for controlling said doors.

18. A car having end portions and supporting trucks therefor, and an intermediate portion pivotally supported at its ends upon said trucks, the flooring of the intermediate portion being in a lower plane than the flooring of the end portions, the end portions opening from the interior thereof into the interior of the intermediate portion.

19. A car composed of end sections and an intermediate section, the floor of the intermediate section being at a lower level than that of the end sections, said intermediate section being pivotally connected at its ends to the end sections, and flexible curtains for closing the space between the proximate ends of adjacent sections.

20. A car composed of end sections including supporting trucks and having doorways through their proximate ends, the side walls of said doorways being inwardly extended toward each other, and an intermediate section with the interior of which said doorways communicate, said intermediate section being swivelly supported at its ends upon the end sections and having doorways in the side thereof.

21. A car composed of end sections including trucks and having doorways through their proximate ends, and doorways in the side thereof at their remote ends, doors for the latter doorways, an intermediate section into which said proximate end doorways communicate, said intermediate section be-

ing swivelly supported at its ends upon the end sections, side doors for the intermediate section and means for controlling said doors.

22. Means for transporting passengers composed of end body portions and an intermediate body portion flexibly connected together and communicating with each other, the intermediate body having a floor level below that of the adjacent bodies, and also having a side entrance.

23. An articulated car comprising two end units and an intermediate passenger-carrying compartment movably suspended between and supported by the end units.

24. In an articulated car, the combination 15 with a pair of end passenger-carrying sections, of an intermediate passenger-carrying compartment flexibly suspended between and supported by the end sections and capable of vertical and lateral move- 20 ment relative to such end sections.

In testimony whereof, I have signed my name to this specification in the presence of two subscribing witnesses.

JOHN LINDALL.
